F. W. LORD.

ANCHORAGE FOR TENNIS NETS AND THE LIKE.

APPLICATION FILED OCT. 11, 1916.

1,239,924.

Patented Sept. 11, 1917.

UNITED STATES PATENT OFFICE.

FREDERICK WAIT LORD, OF NEW YORK, N. Y.

ANCHORAGE FOR TENNIS-NETS AND THE LIKE.

1,239,924.

Specification of Letters Patent. Patented Sept. 11, 1917.

Application filed October 11, 1916. Serial No. 125,114.

To all whom it may concern:

Be it known that I, FREDERICK W. LORD, a citizen of the United States, and resident of the borough of Manhattan, city, county, and State of New York, have invented certain new and useful Improvements in Anchorage for Tennis-Nets and the like, of which the following is a specification.

In securing a tennis net upon a court it is desirable that all of the fastening means and particularly those that are to be introduced into the surface of the court, should be so constructed that their upper surfaces will lie flush with the surface of the court. This is important for when kept in proper condition it is often necessary to roll down the surface of a tennis court or to sweep it clear of loose earth or other foreign matter that might collect thereon. Therefore a securing means that may be permanently engaged upon a court should be so arranged or constructed that the passage of a roller or broom over the court, would not necessitate the removal of the securing means, which removal might tend to break the surface of the court. It is evident then, that a securing means that can be so placed in position that it will become a portion of the surface of the court and that may be rolled or swept without fear of damage, will have certain and definite advantages.

The device, the subject of this invention is intended as a means for securing the net. It may operate in the same manner as the center iron, but without the disadvantages thereof and it may also operate to assist in securing the end posts and it is believed that the method of operation and the advantages to be obtained therefrom will be fully appreciated from the specification which follows.

The following is what I consider a good means of carrying out this invention and the accompanying drawings should be referred to for a complete understanding of the specification which follows.

In the drawings:—

Figure 1 shows a portion of a tennis court with my device in position securing the net.

Fig. 2 is an end elevation of one part of my device.

Fig. 3 a side elevation of a portion of my device.

Fig. 4 shows a completely assembled anchoring unit.

Fig. 5 is an end elevation showing a possible operation of a part.

Similar reference numerals indicate like parts in all the figures where they appear.

At 1, I have shown a tennis net. The net 1, is arranged across the center of a court and over which the ball is caused to pass, while in play. This net may be of ordinary shape and size, as it is not necessary in the use of my invention to change any of the standard equipment which has been so satisfactory in the past.

The net 1, is supported between posts 2 and 3, and guy lines 4 and 5, are usually provided for obtaining a tension on the net and for retaining it in proper position.

It has been found that when sufficient tension is placed upon the guy lines 4 and 5, to hold the net taut, the center portion of the net may be raised too high. To prevent this I place two securing or surface engaging toothed plates 6 and 7, definite distances apart, and between them I extend a flexible wire, cord or chain member 8. This member is secured to the toothed members 6 and 7 and the teeth of the plates 6 and 7, are then forced into the surface of the court and sufficient distances apart to retain the member 8, tight and quite closely adjacent to the surface of the court.

I provide a strap or canvas belt 9, which is provided with a buckle 10, and I pass this strap over the net and under the flexible member 8.

When arranged as shown in Fig. 1, it is only necessary to take up the strap 9, and to secure it by means of its buckle 10, to obtain a satisfactory adjustment of the height of the center portion of the net.

When the net is removed the strap 9, may also be removed, but it will not be necessary to remove the toothed plates 6 and 7, or the wire or chain 8.

Similar means may be employed for securing the guy ropes 4 and 5, and when so employed they will be secured to the ground or the surface of the court a convenient distance away from the base of the posts 2 and 3. The guy ropes or lines will then be fastened to the posts and quite near the top thereof and the other end secured to the flexible member which is arranged between the toothed plates 6 and 7 after which tension may be placed upon the guy ropes to retain the posts in a manner well understood.

The construction of my toothed plates is important and in Figs. 2 and 3, 4 and 5, I have shown their construction. Each of

these members consist of a plate 11, having formed integral therewith a plurality of projecting teeth 12, 13, 14, 15 and 16. The plate may be formed of any suitable material, but I prefer it should be constructed of galvanized sheet iron and the teeth project at an approximate right angle to the surface of the plate.

In one side of each plate, I produce a 10 perforation and in the perforation I secure one end of a chain, wire or other flexible member.

The length of each of these toothed plates may be determined by the peculiar requirements, as may the width and thickness of 15 the material from which they are constructed.

A flexible member secures two toothed plates, as shown in Figs. 1 and 4, and I desire that two plates 6 and 7, or their equivalents, with a connecting flexible member, should be used as a single holding unit and when formed as described and secured together by a flexible member, the members 6 and 7, may be inserted at any desired position 20 and the guy rope or strap or any other device which it is desired to secure, may be passed around the flexible member and held thereby.

In holding down a tennis net, the toothed 30 plates are arranged upon the center line of the court and they should be forced into the surface of the court until their upper surfaces lie flush with the surface of the court. In this position a flexible member is ready 35 to receive the strap or belt 9.

When holding a guy rope, one or two sets of units may be used as shown in Fig. 1, and should be inserted in the manner previously described.

40 My device has advantages over the ordinary pegs in that they provide a multiplicity of engaging points. When tension is applied to the flexible member the tendency is to draw the plates 6 and 7, toward 45 each other, with the result that the teeth of these plates engage with greater firmness the material into which they are inserted.

In Fig. 5, I show that the teeth of the

plates may be deflected. This may occur when the plates are inserted into the sandy 50 or gravelly soil, or into soil having roots or other obstructions, which meet the teeth. This deflection of the teeth is not objectionable, in fact, it may be considered an advantage in causing the teeth to clampingly 55 engage.

I may use my device as an anchorage for any purpose such, for instance, as securing boats to sandy soil. If used for this purpose, it will probably be found desirable to 60 increase the length of the plate 11, and also the length and number of teeth 12, 13 and so forth.

Other modifications may be made within the scope of the appended claims without 65 departing from the principle or sacrificing the advantages of the invention.

Having carefully and fully described my invention what I claim and desire to secure by Letters Patent is:

1. Means for retaining a tennis net, comprising a plurality of plates, each provided with a plurality of teeth, and a flexible member between said toothed plates.

2. Means for retaining a tennis net, comprising a plurality of plates each having a plurality of independent teeth, a flexible member between said toothed plates, and a flexible member adapted to engage a net and said first mentioned flexible member.

3. A device of the character described, comprising a plurality of perforated plates, a plurality of teeth supported thereby and extending at right angles to the surface thereof, and a flexible member secured in 85 said perforation and extending approximately parallel with the surface of said plates, as and for the purpose set forth.

4. A securing means comprising a plurality of toothed plates, a flexible member 90 extending between said plates and secured thereto and a flexible member adapted to engage said first flexible member.

Signed at New York city, this 5th day of Sept. 1916.

FREDERICK WAIT LORD.
